UNITED STATES PATENT OFFICE.

RICHARD W. DAWN, OF DEER LODGE, MONTANA, ASSIGNOR TO W. E. CASTLETON, OF DEER LODGE, MONTANA.

ATTACHMENT FOR STEAM BOARDS.

Application filed March 19, 1926. Serial No. 96,018.

The object of this invention is to provide means for holding a garment or piece of fabric on a steam board or steam press, so that the user of the device may have one hand free for brushing or similar purposes, while he holds the garment with the other hand and pulls it longitudinally of the board, in connection with the brushing or cleaning operation under way.

10. A further object is to provide a device especially adapted to engage the under side of a pile fabric, for the purpose of holding it in position, without the necessity of employing the hands for that particular purpose, or using pins or the like in order to retain any portion of the garment in position on the board.

20. A further object is to provide a retaining attachment, comprising an element of resilient material having teeth formed along one edge thereof, the ends of the attachment being deflected under the board, and provided with finger or thumb engaging members.

25. With the foregoing and other objects in view, the invention consists in the novel construction and arrangement of elements described, illustrated and claimed, it being understood that modifications may be made within the scope of the claims, without departing from the spirit of the invention.

30. In the drawings forming part of this application,

Figure 1 is a perspective view of the device.

35. Figure 2 is a view in top plan, the element being operated upon being shown in dotted lines, and it being assumed that the under side of this fabric or garment is in engagement with the teeth, deflected in the direction shown.

40. Figure 3 is a section on line 3-3 of Figure 1.

Figure 4 is a section on line 4-4 of Figure 1.

45. The attachment comprises a strip 10 of resilient material, and may be regarded as a light steel spring, the middle portion of which is substantially flat, but is capable of being made to conform to the curvature

of the board, as indicated in Figure 3. One edge portion has formed thereon, or carried thereby, a series of teeth 11, deflected toward the opposite edge of the resilient strip, and adapted to engage the under side of the garment or the fabric being steamed and 55 brushed.

The end portions of the strip 10 are curved downwardly at 12, and are thence deflected toward each other to provide resilient clamping portions 13 adapted to engage the 60 under side of the board. The strip is again deflected, to form thumb members 14, by means of which the user applies and releases the device from the edges of the board.

This attachment is preferably applied in 65 about the position indicated in Figure 2, with reference to the left hand end of the board 16 there shown, it being understood that the position on the board at a particular time, is determined by the article being steamed, 70 but if the latter is of about the proportions shown in dotted lines in Figure 2, and designated 17, one portion thereof should project beyond the end 16' of the board sufficiently to permit the operator to grasp the 75 garment or fabric, and pull the latter toward the left in Figure 2, whereby proper engagement with the hooks 11, deflected in the direction shown, will result.

The device is suitable for use in connection with all pile fabrics with which the steam board or steam press is employed, and no injury to the garment or fabric will result, because of the form of the engaging devices, and the possibility of keeping the 85 points of the teeth 11 away from the outer surface of the garment, the adjacent portion of which lies flat on the surface of strip 10. Finger prints on the surface are avoided.

90. Having thus described the invention, what is claimed is:

1. A device of the class described, comprising a strip, downwardly extending clamping members carried by the ends of the strip and turned toward each other, and fabric engaging devices carried by the upper surface of the strip.

2. A device of the class described, comprising a strip having teeth on one edge thereof, deflected towards the opposite edge, and resilient clamping members carried by the ends of the strip.

3. A device of the class described, comprising a strip having teeth formed on one edge thereof, deflected towards the opposite edge, and resilient clamping and thumb en-

gaging members carried by the ends of the strip.

4. A device of the class described, comprising a resilient strip having teeth on one edge thereof, and resilient clamping members carried by the ends of the strip and turned towards each other.

In testimony whereof I affix my signature.
RICHARD W. DAWN.
